FIRE EXTINGUISHER

Frank Mossberg, Attleboro, Mass., assignor to
 Mossberg Pressed Steel Corporation, Attleboro,
 Mass., a corporation of Massachusetts

Application July 3, 1934, Serial No. 733,544

3 Claims.

(Cl. 169—26)

This invention relates to fire extinguishers, and particularly to improvements in that type of extinguisher which is adapted to release a liquid fire extinguishing agent automatically when the

5 temperature in the vicinity of the apparatus rises to a predetermined point.

In apparatus of the type described, a receptacle is provided for a fire extinguishing liquid, for example, carbon tetrachloride, and a gas generating 10 agent such as an aqueous solution of ammonia. The apparatus is provided with a sprinkler head or similar distributor and an outlet leading thereto, which is normally sealed but is adapted to be released when a fire occurs. Pressure developed 15 by the gas generating agent when the temperature rises forces the fire extinguishing agent through the outlet when the latter is released. The fire extinguishing agent is distributed over the surrounding surface.

20 It is the object of the present invention to provide an improved apparatus wherein the release of the outlet under predetermined conditions is made more certain and dependable, thereby increasing the efficiency of the apparatus.

25 Another object of the invention is the provision of an improved outlet controlling means adapted to assure increased sensitiveness to temperature in the vicinity of the apparatus.

Other objects and advantages of the invention 30 will be better understood by reference to the specification and accompanying drawing, in which

Fig. 1 is a vertical section through an apparatus embodying the invention;

Fig. 2 is an enlarged vertical section through 35 the sprinkler head;

Fig. 3 is a section on the line 3—3 of Fig. 2; and

Fig. 4 is a plan detail of an element of the 40 sprinkler head.

In carrying out the invention, I provide a receptacle 5 which is preferably made of aluminum, particularly if the liquids used therein consist of carbon tetrachloride and aqueous ammonia, because aluminum resists the corrosive effect of these liquids in combination. Other materials 45 may be used for the container, which may be of any shape or size to meet particular requirements. The receptacle 5 is provided preferably with a bail 6 to facilitate suspension. The position of the receptacle may be reversed so that the discharge is downwardly rather than upwardly, as indicated.

An outlet pipe 7 extends from a point near the bottom of the receptacle 5 to the top thereof, and terminates in a sprinkler head 8. If the sprinkler 50 head is disposed at the bottom rather than at the

top of the receptacle 5, the pipe 7 may be omitted, being unnecessary when the contents are permitted to escape from the bottom of the receptacle.

The sprinkler head 7 is of special construction 5 to embody the "dual control" features of Patent No. 1,736,255, to which my improvements more particularly relate. An opening 9 in the sprinkler head receives a nozzle 10. This nozzle is made of a steel alloy containing chromium in the proportion of, for example about 18-8%, or similar alloy designated as "stainless steel", which resists corrosion and is capable of receiving an adhering ring of low melting point solder. The nozzle is provided with a central bore 11 which is enlarged 15 at the lower end. The bore is closed at its outer end by a cap 12 also preferably of "stainless steel" which is secured by a ring 13 of solder having a composition well known in the art and adapted to be melted at a temperature which ensures the 20 release of the outlet when a fire occurs in the vicinity of the apparatus. The cap 12 is provided preferably with an indentation 14 which centers it by cooperation with the bore 11 on the top of the nozzle. The outlet is thus normally hermetically sealed until a fire occurs, but is then released 25 automatically.

Within the nozzle 10 is a thimble 15 secured by a press fit and having an end 16 directed inwardly and preferably conical in form, with openings 17 30 disposed about it. The openings permit egress of the liquid contents of the extinguisher and prevent the liquid from acquiring a swirling motion which otherwise would tend to throw it outwardly before it strikes a deflector 18 at the top of the 35 sprinkler head 8. When the liquid is released as described, it issues as a direct stream from the mouth of the nozzle and strikes the deflector which causes it to spread in all directions about the apparatus. The even distribution thus effected ensures the proper functioning of the extinguisher.

As a further control of the operation of the extinguisher, I provide a diaphragm 19 of thin metal, preferably gold foil, between two washers 45 20 and 21, the former having lugs 22 to engage slots 23 and 24 in the diaphragm 19 and opposing washer 21 respectively. The washers 20 and 21 are held between the shoulders 25 and 26 on the sprinkler head and the co-operating part 27 which 50 is threaded to connect thereto and supports the outlet pipe 7. The upper washer 20 has a large opening 28, and the lower washer 21 a smaller opening 28'. The diaphragm is adapted to be ruptured when the pressure rises to a predeter- 55

mined point in the receptacle 5, thus affording "dual control" and preventing release of the liquid contents before a sufficient pressure is developed. The diaphragm may be made of other metal such as platinum, silver or aluminum.

To protect the diaphragm from premature rupture before the cap 12 is released, I preferably fill the bore of the nozzle above the diaphragm with a material 29 which is a liquid or semi-liquid 10 at the temperature at which the apparatus is designed to operate. Vaseline and glycerin are suitable materials. Low melting point waxes and similar materials can be used. When the conditions for operation exist, the cap 12 is released by 15 the melting of the solder, the diaphragm 19 is ruptured by the pressure generated within the receptacle, and the liquid contents force the material 29 from the bore and are ejected against the deflector 18 which distributes the liquid over 20 rounding surfaces.

The structure as described has been subjected to many practical tests for fire extinguishing characteristics and is certain and effective in operation. It likewise ensures the protection and 25 preservation of the contents of the receptacle indefinitely, so that it is ready and dependable when a fire occurs. None of the contents can escape until the predetermined fire conditions occur, and consequently the maximum possible protection is 30 assured at all times.

The various advantages of the invention are set forth herein, and these and other advantages may be attained with numerous modifications of the structure without departing from the invention or sacrificing the advantages thereof.

I claim:

1. In a fire extinguisher, a receptacle, a sprinkler head connected thereto, a nozzle of non-corrosive steel in the sprinkler head, a cap adapted to close the outlet from the nozzle, means sen- 40

sitive to temperature of predetermined degree, normally holding the cap in nozzle-closing position and adapted to release the cap at such temperature, and a frangible diaphragm at the inner end of the nozzle, said diaphragm being rupturable in response to a predetermined pressure, the space between said diaphragm and said cap being substantially filled with a material which is substantially liquid at such temperatures and which under normal temperature conditions is expellable but maintained against expulsion by said cap. 5

2. In a fire extinguisher, a receptacle, a sprinkler head connected thereto, a nozzle, a cap adapted to close the outlet from the nozzle, means sensitive to temperature of predetermined degree, 10 normally holding the cap in nozzle-closing position and adapted to release the cap at such temperature, and a frangible diaphragm at the inner end of the nozzle, said diaphragm being rupturable in response to a predetermined pressure, the 15 space between said diaphragm and said cap being substantially filled with a material which is substantially liquid at such temperature and which under normal temperature conditions is expellable but maintained against expulsion by said cap. 20

3. In a fire extinguisher, a receptacle, a sprinkler head connected thereto, a nozzle, a cap adapted to close the outlet from the nozzle, means sensitive to fire temperatures normally holding the cap in nozzle-closing position and adapted to release the cap at such temperature, a frangible diaphragm in the inner end of the nozzle, said diaphragm being rupturable in response to a predetermined pressure, and means between said diaphragm and said cap for normally reinforcing 35 said diaphragm, said means under normal temperature conditions being expellable but maintained against expulsion by said cap. 40
